UNITED STATES PATENT OFFICE.

LESTER C. EASTMAN AND AUSTIN R. EASTMAN, OF SILVERTON, OREGON.

FIRE ESCAPE.

Application filed April 23, 1925. Serial No. 25,854.

This invention relates to an improved fire escape of the chute type and has for its object to provide a device of this character, which will convey persons from upper stories to the ground floor, with least congestion and delay.

A further object of our invention is to provide a fire escape of the rolled edge chute type, that may be easily installed at the side of a building and will be composed of few parts and one that will not easily get out of repair and may be used by all classes of people.

A further object of our invention is to provide a fire escape wherein the same will be particularly adapted for use in school buildings, factories and the like, wherein a large number of people are to be discharged quickly and without delay.

A further object of our invention consists in the elevated horizontal seat provided for the entrance, to the fire escape slide, wherein users may enter the fire escape from an elevated seat arrangement which connects directly into the slide, obviating the necessity of their entrance into the slide from a position on line with the level of the platform entrance.

A further object of our invention consists in a new and improved bracket support disposed on the under side of the main slide and adapted to engage with the hinge band adapted to maintain the main slide in position.

A further object of our invention consists in the placing of a structural member along the rolled edge of the main slide member to afford additional rigidity thereto and to eliminate the possibility of the user of the slide becoming mangled from contacting with what would otherwise be the unsupported edge of the sheet forming the slide.

A further object of our invention consists in a new and simplified construction adapted to easy erection and one that will be easily adapted to the wall structure of the building upon which the same is to be erected.

A further object of our invention consists in the simple and efficient structure created and one that will not easily get out of order.

A further object of our invention is to provide a railing around the same and a

platform entrance and supporting means on the same.

While the primary object of our invention is for the purpose of use in schools, theatres, factories and the like yet the same may be used for the handling of packages and the like in warehouses, department stores, and other places wherein it is found desirable, or necessary, to bring materials to a lower level. When used for such purposes the same may be deposited upon the raised seat section which may be placed at the approximate carrying height of the worker depositing the same.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings—

Fig. 1 is a side elevation of our fire escape shown in position upon the side of a building and an opening leading from the building on to the platform entrance.

Fig. 2 is fragmentary plan view of the mechanism shown in Fig. 1.

Fig. 3 is a fragmentary side elevation taken on line 3—3 of Fig. 2, looking in the direction indicated.

Fig. 4 is a sectional view taken on line 4—4 of Fig. 3, looking in the direction indicated.

Fig. 5 is a fragmentary side elevation of the slide shown in position and being supported by a new and improved bracket support.

Fig. 6 is a sectional view taken on line 6—6 of Fig. 5, looking in the direction indicated.

Fig. 7 is a detailed, partial sectional view of the bracket support, illustrating the slide member removed therefrom.

Fig. 8 is a detached side view of the bracket support, illustrating the band for supporting the bottom portion of the slide member.

Fig. 9 is a sectional view taken on line 9—9 of Fig. 7, looking in the direction indicated.

Fig. 10 is a fragmentary sectional view of

a portion of the slide illustrating the method of reinforcing the same with a structural member.

Like reference characters refer to like parts, throughout the several views.

1 is the wall of the building having attached thereto a suitable supporting bracket 2, adapted to be attached to the wall structure and to support the main slide comprising the fire escape. A platform 3, is disposed at the upper end of the fire escape and is supported upon the wall structure by suitable brackets, made of metal or any other fire resistant material. A suitable opening 5, as a pair of doors, is disposed through the wall structure and at the upper end of the fire escape; an end closure 6, is disposed at the upper end of the fire escape. The platform 3, extends from the wall of the building, completely across the upper end of the entrance end of the fire escape, and is adapted to support the users of the same as they emerge through the opening 5, and step upon the platform 3.

23 In fire escapes as they are used at the present time, an opening leads directly from the platform 3, into the slide at the floor line, which with timid people and children, makes the entrance into the slide extremely slow, because of the apparent entrance into a hole leading directly from the platform. In our new and improved fire escape the main portion of the slide runs a substantial distance above the platform as shown in Fig. 1, terminating in an approximate horizontal seat member 7, at an elevation approximately that of a seat upon which the users would sit in a normal position. This horizontal portion 7, as shown in Fig. 3, has the outer upturned wall of the slide 8, as shown in Fig. 3, which leads directly into the main slide proper, so that when the user reclines in a sitting posture upon the horizontal portion 7, as shown in Fig. 3, 40 placed into the slide channel proper and entrance had into the slide from a sitting or reclining posture, is accomplished with least resistance. This we have found, greatly increases the speed, or the number of people, 45 that can be handled through our fire escape in a given time. To afford additional safety to our new and improved fire escape we have provided the usual rolled edge 9, extending the full length of the fire escape 50 with a structural support along the edge. A substantial distance is provided between the fire escape proper and the wall of the building, as shown at 10, in Fig. 4, to permit of the free and easy entrance from the building on to the platform 3, and to the entrance into the slide of the fire escape. To further increase the rigidity of the escape and to lengthen the span, that the same may be made between supporting brackets, we 55 have supplied a structural member 11, to

which the longitudinal edges of the sheets forming the slide are attached by suitable fastening means; this affords additional rigidity to the slide and increases the length of span between the brackets and at the same time makes the same safer for the user thereof.

In the erection of fire escapes of this character, we have experienced considerable difficulty by former methods in aligning the supporting brackets with the main slide; to overcome this difficulty we have provided a bracket member, as shown at 2 in Fig. 5, wherein the same terminates in a socket at the bottom of the triangular shaped opening 12; the upper end of the socket member 12, is secured to the structure member 11, by suitable fastening means as bolts or rivets, and having engaged therewith a strap 13, having pin projections 14, at the ends thereof, adapted to engage within the sockets formed at the lower ends of the openings 12, which locates the same.

This pin projection 14, in its engagement with the socket 12, is adapted to journal 99 therein and the strap 13, being made of flat stock is adapted to adjust itself to the angle of the bottom of the slide and because of the journal connection with the bracket support compensates for the angle of the slide member. A cross bar 15, connects the uprights 16 and 17, and is secured to each upright by suitable fastening means, such as bolts; and to further increase the rigidity of the bracket support, a gusset bar 19, 100 is disposed within the angle formed by each of the uprights 16 and 17 and the cross bar 15. The bracket support may be supported with an angle brace 20, or with posts 21, and 22, as the same approaches the 105 terminal level. In order to permit the occupants thereof to come to a stop before leaving the slide the same may change the angle of the slide near the bottom so that a desired stop may be made. Any desired angle 110 as shown at 23, may be made.

While the form of mechanism herein shown and described is admirably adapted to fulfill the objects primarily stated, it is to be understood that it is not intended 115 to confine the invention to the one form of embodiment herein shown and described, as it is susceptible of embodiment in various forms, all coming within the scope of the claims which follow.

We claim:

1. A new and improved fire escape, comprising an inclined slide disposed between an upper floor exit of a building and the ground, supports for said slide; and an entrance thereto formed by extending a section of said slide above the floor level of said exit, and terminating the same in a horizontal section the inner side wall of that section of the slide extended above the floor 125 130 135

level of said exit and of said horizontal terminus having been removed to form a seat like section, a platform mounted on the inner side of said slide and below the 5 level of the horizontal seat-like section, and a closure at the outer end of said horizontal seat-like section.

2. A new and improved fire escape, comprising and inclined slide disposed between 10 an upper floor of a building and the ground, and a support therefor, comprising upright members disposed each side of the slide, having their upper ends attached to the outer edges of the slide and their lower ends 15 mounted on a cross bar disposed upon a suitable support, sockets formed in said uprights adjacent their upper ends, a swinging yoke, having its outer ends pivotally maintained in said sockets disposed between said 20 uprights, and gusset braces disposed between the upright members and said cross bar.

3. A new and improved fire escape, of the slide type, a support therefor, comprising 25 a cross bar mounted on a suitable support, uprights disposed each side of the slide, the upper ends of which are secured to the outer edges of the slide, the lower ends thereof attached to said cross bar, sockets 30 formed in said uprights adjacent their upper ends, and an adjustable yoke, having pins disposed thereon adjacent its ends which are adapted to be pivotally maintained within said sockets pivotally disposed 35 between said uprights.

4. A new and improved fire escape, comprising an inclined chute terminating at its upper end in a seat like section, a platform mounted adjacent said seat like section and below the level thereof, and and end closure 40 disposed at the outer ends of said seat like section and said platform.

5. A new and improved fire escape, comprising an inclined chute, there being an open section in one side of said chute to 45 form a seat-like section; a platform mounted below said seat, the inner edge of which is positioned in vertical alignment with the edge of the seat, and extending outwardly therefrom, and a closure mounted at the 50 outer ends of said seat-like section and said platform.

6. A new and improved fire escape, comprising an inclined chute disposed between an upper floor exit of a building and the 55 ground, there being an open section formed in the inner side wall of the chute at its upper end to form a seat like section, said seat like section being above the floor level of the building exit, a platform mounted below 60 said seat-like section, one edge of which is positioned in vertical alignment with the edge of the seat-like section, said platform extended outwardly therefrom, and an end closure at the outer ends of said platform 65 and said seat-like section.

7. A new and improved fire escape, comprising an inclined chute disposed between an upper floor exit of a building and the 70 ground, the lower end terminating in a substantially horizontal section; there being an open section formed in the inner side wall of the chute at its upper end to form a seat like section, said seat like section being above the floor level of the building exit, a platform mounted below the seat-like section, one edge of which is positioned in vertical 75 alignment with the edge of the seat-like section, said platform extended outwardly therefrom, and an end closure for the outer ends of said platform and said seat like section.

LESTER C. EASTMAN.
AUSTIN R. EASTMAN.
